Primary Examiner — W. A. Teddy Falloway*Assistant Examiner* — Sarah J Ault(74) *Attorney, Agent, or Firm* — Leason Ellis LLP(57) **CLAIM**

The ornamental design for a vase as shown and described.

DESCRIPTION

FIG. 1 is a front elevation view of a rotationally symmetric vase according to our new design;

FIG. 2 is a top plan view thereof;

FIG. 3 is a sectional view taken along line 3'-3' of FIG. 1;

FIG. 4 is an enlarged front elevation view of a component of a rotationally symmetric vase according to our new design;

FIG. 5 is an enlarged top plan view of a component of a rotationally symmetric vase according to our new design;

FIG. 6 is an enlarged front elevation view of a component of a rotationally symmetric vase according to our new design; and,

FIG. 7 is an enlarged top plan view of a component of a rotationally symmetric vase according to our new design. The grayscale shading depicts a contrast which is part of the claimed design without claiming any particular color.

1 Claim, 7 Drawing Sheets
